UNITED STATES PATENT OFFICE.

ERNEST MOORE VIQUESNEY, OF SPENCER, INDIANA.

DESIGN FOR AN ASH TRAY OR THE LIKE.

Application filed August 14, 1924. Serial No. 10,457. Term of patent 14 years.

To all whom it may concern:

Be it known that I, ERNEST M. VIQUESNEY, a citizen of the United States, and a resident of Spencer, in the county of Owen and State of Indiana, have invented certain new, original, and ornamental Designs for Ash Trays and the like, of which the following is a specification, reference being had to the accompanying drawing, forming a part thereof.

In the drawing:

Figure 1 is a view taken from the rear and to one side of my design, and

I claim:

The ornamental design for an ash tray or the like, as shown.

ERNEST MOORE VIQUESNEY.
